CLAIM

The ornamental design for a hard hat clip, as shown and described.

DESCRIPTION

FIG. 1 is a perspective view of a hard hat clip showing my new design;

FIG. 2 is a perspective view comparable to FIG. 1 except on an enlarged scale;

FIG. 3 is a front elevational view of FIG. 2, the rear being a mirror image thereof;

FIG. 4 is a left side elevational view of FIG. 2;

FIG. 5 is a right side elevational view of FIG. 2;

FIG. 6 is a top plan view of FIG. 2; and,

FIG. 7 is a bottom plan view of FIG. 2.

The broken lines in drawing represent environmental subject matter that forms no part of the claimed design.
